UNITED STATES PATENT OFFICE.

CLARENCE E. MEHLHOPE, OF WINNETKA, ILLINOIS.

GEARING.

1,334,045.

Specification of Letters Patent. Patented Mar. 16, 1920.

Application filed March 30, 1918. Serial No. 225,705.

To all whom it may concern:

Be it known that I, CLARENCE E. MEHLHOPE, a citizen of the United States, and a resident of Winnetka, in the county of Cook and State of Illinois, have invented certain new and useful Improvements in Gearing; and I do hereby declare that the following is a full, clear, and exact description thereof, reference being had to the accompanying drawings, and to the letters of reference marked thereon, which form a part of this specification.

This invention relates to improvements in gearing and consists of the matters herein-after described and more particularly pointed out in the appended claims.

The gearing is designed particularly for use in connection with a washing machine of the kind known as a "pounder" washer or a "vacuum" washer, in which a spider having a tool on each of its arms, is removably attached to the top end of an operating shaft or plunger, by means of which the spider and its associated tools is given a vertical, reciprocating movement and in most cases at the same time, an alternating, rotary movement.

The object of the invention is to provide an economical and efficient gearing for the purpose intended, by means of which the power, both to vertically reciprocate the operating shaft or plunger and also to alternately rotate the same, is applied directly to said shaft, from beneath the tub.

The many advantages of the invention will appear more fully as I proceed with my specification.

In the drawings:

Figure 1 is a view representing a vertical section through a washing machine of the kind mentioned, provided with my improved gearing for actuating the operating shaft of the washing machine.

Fig. 2 is a view illustrating on an enlarged scale, a detail, horizontal section through the same, the plane of the section being indicated by the line 2-2 of Fig. 1.

Fig. 3 is a view illustrating on an enlarged scale, another horizontal section through the same, the plane of the section being indicated by the line 3-3 of Fig. 1.

Fig. 4 is a view illustrating on an enlarged scale, a detail, vertical section

through a part of my improved gearing, the plane of the section being indicated by the line 4-4 of Fig. 1.

Fig. 5 is a detail, horizontal, sectional view on an enlarged scale, which will be more specifically referred to later.

Fig. 6 is a detail, perspective view, which also will be more specifically referred to later.

Referring now to that embodiment of my invention illustrated in the drawings:— 10 indicates the tub of a washing machine 65 which has the usual supporting legs 11. Said legs are braced in pairs near their bottom ends, by bars 12, which in turn are connected together by a platform 13. The tub 10 has the usual bottom wall 14, and fixed 70 top wall part 15, to which is hinged a lid 16. The tub together with its bottom wall 14 and the platform 13, constitute the support for the gearing.

17 indicates the upright operating shaft 75 of the washing machine. This shaft, which has a head 17^a at its top end and a part 17^b of reduced diameter at its bottom end, extends through a centrally arranged hole 14^a 80 in the bottom wall of the tub and has sliding bearing at its top end within the tub, in a plane above the usual water line therein, in an upright sleeve 18. This sleeve has a radial flange 18^a, and said flange engages upon the top surface of the bottom wall 14 85 and is fixed thereto in a manner soon to be described.

Fixed to the bottom surface of the bottom wall 14, in line with the flange 18^a of the sleeve 18, is an apertured bracket plate 90 19. This bracket plate has depending arms 20, which terminate in a bearing sleeve 21 arranged in alinement with the sleeve 18, and in which the reduced bottom end part 17^b of the shaft 17 has sliding bearing. The 95 sleeve 21 has a laterally extending stud 22, the purpose of which will soon appear.

Bolts 23 extend through the bottom wall 14 and through the flange 18^a and bracket plate 19 respectively, to securely affix the 100 sleeve 18 and the bracket plate 19 to said bottom wall. Preferably, I interpose a compressible, annular gasket 24 between the flange 18^a and the top surface of the bottom wall 14, so that when the nuts on the bolts 105 23 are screwed home, the gasket 24 is com-

pressed and the sharpened edge 18^b of the flange 18^a bites into the bottom wall 14 in a manner insuring against a leakage of water through the hole 14^a in the bottom wall 14 (see Figs. 1 and 4). This construction is also advantageous in that it presents no exposed edges on the sleeve for engagement with the clothing being washed.

Fixed to the top end of the upright shaft 10 just below the head 17^a is a squared sleeve 25 that has a radial flange 26. This squared sleeve is adapted to receive the hub 27^a of a spider 27, the hub 27^a having a squared hole to fit the sleeve 25. The spider 27 has 15 radially extending arms 27^b (as shown in this instance, three in number) and from the outer end of each arm depends an inverted cup-shaped tool 28 of the familiar kind. A latch 29 is pivoted at one end to the hub 27^a 20 of the spider, so that it may be swung to engage beneath the head 17^a of the shaft to lock said spider against any movement on the shaft 17.

30 indicates a bell crank lever which is 25 fulcrumed in a depending bracket casting 31 fixed to the bottom wall 14 and the upright side wall of the tub body 10. This lever which is capable of a rocking movement, is operatively connected to the operating shaft 17 and to a high speed fly wheel in a manner soon to appear. The normally upright arm 30^a of this bell crank lever has a socket 30^b at its top end, in which is secured an operating handle 30^c, while the 30 normally horizontal arm 30^d of said bell crank lever, has a forked end 32 (see Figs. 5 and 6), which embraces a sleeve 33 fixed to the shaft 17 just above its reduced bottom end part 17^a. 34, 35 indicate the tines of 35 40 the fork. The tine 34 has a countersunk hole 35^a and through the hole 35^a the sleeve 33, shaft 17 and the slot 34^a, extends a pin 36 which has a cylindrical head 36^a that is normally located in the countersunk part of 45 the hole 35^a.

The connection between the forked end 32 of the arm 30^d and the shaft 17 just described, is such that when a rocking movement is imparted to the lever 30 as a whole, 50 a positive up and down movement is imparted to the forked end of the arm 30^d and consequently to the operating shaft 17. At the same time, by reason of the horizontal displacement of the pin 36^a in the rocking movement of the arm 30^d from its topmost to its bottom-most position, a rotative, 55 swinging movement is imparted to the shaft 17, in one direction when the arm 30^d is moving upward and in the other direction when 60 the said arm is moving downward. The engagement of the pin 36 in the slot 34^a of the tine 34 and head 36^a of said pin in the countersunk hole 35^a in the tine 35, provides for the positive engagement of the lever on 65 both sides of the shaft 17 without interfer-

ing with the alternating movement imparted to the shaft in the up and down movement of the arm 30^a of the bell crank lever 30.

The high speed fly wheel mechanism before mentioned, is constructed and is operatively connected to the bell crank lever 30 as follows. 37 indicates a bevel gear which is journaled on the laterally extending stud 22 on the bracket sleeve 21. This bevel gear meshes with a bevel pinion 38 made integral with a horizontally disposed fly wheel 39 which is rotatively mounted on an upright, tubular bearing sleeve 40 made integral with a bracket plate 41 that is fixed to the platform 13 before mentioned. A suitable antifriction bearing 42 is interposed between the bracket 41 and the fly wheel 39. The upright, tubular bearing sleeve, is coaxially arranged with the upright shaft 17 and provides a guide for the reduced part 17^a of said shaft, in the movement of said shaft as before described and the platform 13 is apertured in line with the bearing sleeve 36 to permit of the full movement of said shaft.

90 The bevel gear 37 has a crank stud 37^a to which is connected one end of a pitman 43. The other end of said pitman is connected to the bottom end of a swinging lever or arm 44 which is pivoted at its top end to a bracket 45 fixed to the side wall of the tub 10 in substantially the plane of the bottom wall 14 thereof. In the arm 44 near its top end, is provided a slot 46 in which is engaged a laterally extending pin 47 on the 95 upright arm 30^a of the bell crank lever 30.

When a rocking movement is imparted to the bell crank lever 30, a swinging movement is imparted through the slot and pin connection 46, 47 to the arm 44, which swinging movement is translated by the pitman 43, into a rotary movement of the bevel gear 37, and of course a similar rotary movement is imparted to the fly wheel at high speed through the bevel pinion 38.

100 It is apparent from the construction just described, that all of the mechanism is supported on the tub and its legs, thus leaving the lid 16 free from any weight, with the exception of a cap 16^a that covers a hole 16^b in said lid, which provides room for the top end of the shaft 17 when said shaft has been raised to its topmost, operative position, as before described.

110 In addition to the advantage of having a lid which is easy to open, the fly wheel, which is quite heavy, is so placed as to bring the center of gravity close to the floor upon which the washing machine stands and therefore there is no danger of the machine tipping over during the operation of the bell crank lever. Again, by locating the fly wheel as described, it is protected against breakage by the legs 11 during shipment.

115 120 While in describing my invention, I have 130

referred to certain details of mechanical construction and arrangement of parts, I do not wish to be limited thereto except as may be pointed out in the appended claims.

5 I claim as my invention:

1. In a gearing, in combination with a support having a bottom wall, an operating shaft or plunger extending through said bottom wall into said support and capable of a vertical, reciprocating movement, a lever having an arm adapted for actuating said shaft or plunger, said lever arm having a fork embracing said shaft or plunger and operatively connected thereto, a fly wheel, 10 gearing for actuating said fly wheel at high speed, and means connecting said lever with said high speed gearing.

2. In a gearing, in combination with a support, an operating shaft or plunger extending into said support and capable of a vertical, reciprocating movement, means providing vertically alined bearings for said shaft or plunger, a lever pivoted on said support and having an arm adapted for actuating said shaft or plunger, said lever arm having a fork embracing said shaft or plunger and operatively connected thereto, a fly wheel located in a plane below said support, gearing for operating said fly wheel 25 at high speed, and means operatively connecting said lever with said high speed gearing.

3. In a gearing, in combination with a support having a bottom wall, an operating shaft or plunger extending through said bottom wall into said support and capable of a vertical, reciprocating movement, a bell crank lever pivoted on said support and having an arm connected to said operating shaft or plunger, a fly wheel located below said support, gearing for operating said fly wheel at high speed, a swinging arm pivoted on said support and actuated from said bell crank lever, and means connecting said swinging arm with said high speed gearing.

4. In a gearing, in combination with a support having a bottom wall, an operating shaft or plunger extending through said bottom wall into said support and capable of a vertical, reciprocating movement, top and bottom alined bearing sleeves fixed to said bottom wall for said shaft or plunger, a bell crank lever pivoted on said support, and having an arm connected to said operating shaft or plunger, a horizontally disposed fly wheel located below said support in axial alinement with said operating shaft, gearing for operating said fly wheel at high speed, a swinging arm pivoted on said support and actuated from said bell crank

lever, and means connecting said swinging arm with said high speed gearing.

5. In a gearing, in combination with a support having a bottom wall, an operating shaft or plunger extending through said bottom wall into said support and capable of a vertical, reciprocating movement, alined top and bottom bearing sleeves fixed to said bottom wall and in which said shaft has 65 a sliding bearing, a bell crank lever pivoted on said support and having an arm connected to said operating shaft or plunger below said bottom wall, a laterally extending stud on said bottom bearing sleeve, a bevel 70 gear on said stud, a horizontally disposed fly wheel located below said support in axial alinement with said operating shaft, a bevel pinion on said fly wheel meshing with the said bevel gear, and means connecting 75 said bevel gear with said bell crank lever.

6. In a gearing, for washing machines and the like, comprising in combination with a support having a bottom wall, an operating shaft extending through said bottom wall into said support and capable of a vertical, reciprocating movement and of an alternating rotary movement, a lever pivoted to said support near its bottom, and means directly connecting the lever arm 85 with said operating shaft or plunger below said bottom wall by which the up and down movement of said lever arm is caused to vertically reciprocate said operating shaft, and the horizontal displacement of the means 90 connecting said lever arm with said shaft is used to impart an alternating rotary movement to said shaft.

7. In a gearing, for washing machines and the like, comprising in combination 100 with a support having a bottom wall, an operating shaft extending through said bottom wall into said support and capable of a vertical, reciprocating movement and of an alternating rotary movement, a bell 105 crank lever pivoted to said support near its bottom and having an arm embracing said operating shaft, and a pin extending through said shaft and connected to said arm whereby the up and down movement 110 of said arm imparts both a vertical reciprocating movement and an alternating rotary movement to said operating shaft.

In testimony that I claim the foregoing as my invention I affix my signature, in the 115 presence of two witnesses, this 28th day of March, A. D. 1918.

CLARENCE E. MEHLHOPE.
